FLIER CONSTRUCTION

Michael J. McHale, Scranton, Pa.

Application May 29, 1933, Serial No. 673,547

13 Claims. (Cl. 117—23)

My invention relates to improvements in flier blocks and more particularly to an arrangement whereby the flier wires are attached to a flier block.

In my applications, Serial Numbers 554,312, filed July 31, 1931 and 657,691, filed Feb. 20, 1933, there is disclosed a pre-formed flier wire, securing means therefor, and an improved flier block having a removable foot. The present invention is an improvement over the disclosures of the above mentioned applications and comprises a flier block formed with a tapered peripheral groove, the block being slotted and adapted to receive a separate pre-formed wire loop, the ends of which seat in the block and securely lock the flier wire in the operative position. Means are also provided for locking the block to a bobbin or its associated spindle.

An object of my invention is to provide an improved flier block wherein the flier wire is securely fastened to the flier block by means of a separate locking wire.

Another object of my invention is to provide a flier block having a tapered peripheral groove formed therein whereby the flier wire is wedged against the surfaces of the groove when the wire locking means is placed in the operative position on the block.

Yet another object of my invention is to provide a novel flier block structure having mutually interlocking means adapted to maintain the flier wire on the block and additional means to attach the block to a bobbin.

Still another object of my invention is to provide an improved flier block assembly wherein the locking means for the flier wire also acts as a thread tensioning and guiding means.

A still further object of my invention is to provide an improved flier block which is of general application in connection with various types of flier wires and bobbins.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular

constructions, which for the purpose of explanation, have been made the subject of illustration.

In the drawing, like numerals refer to similar parts throughout the several views, of which

Figure 1 is an elevational view partly in vertical section of a bobbin provided with a flier block having a flier wire and locking means therefor.

Fig. 2 is an elevational view partly in vertical section of a bobbin and associated retaining bushing, showing a modification of the improved flier block.

Fig. 3 is a perspective view of an improved pre-formed flier wire.

Fig. 4 is an enlarged sectional view along line 4—4 of Fig. 5; and

Fig. 5 is a plan view of Fig. 1, with the flier fastening means removed.

Referring to the drawing and more particularly to Fig. 1, there is disclosed a bobbin 1, mounted upon a spindle 2 having a tapered upper section 3 adapted to support a freely rotatable flier block designated generally by numeral 4. The flier block is centrally apertured and the body portion thereof is provided with flanges 5 and 6, defining a peripheral flier wire receiving groove 7. It will be noted that the upper flange 5 is undercut as at 8, and that the upper surface of lower flange 6 is horizontal. The purpose of this arrangement is to enable a flier wire to wedgingly engage with the surfaces of the flanges when it is attached to the block as will be described more fully hereinafter.

Seated in the peripheral groove 7 is a flier wire having arms 9 with vertical portions 10 provided with eyelets 11. As more clearly shown in Fig. 3, the flier wire is also provided with a central block engaging section 12 and offset portions 13 adjacent said section.

Referring to Figs. 4 and 5, it will be seen that the block is further provided with a slot 14 extending across the top thereof and of a depth greater than the width of the groove 7. As shown in Fig. 5, the slot extends into the bottom flange 6 forming a slotted portion or recess 15. In line with the slot 14 and on either side of the central aperture of the block, openings 16 are formed in the flange 6, adapted to receive the flier wire locking means.

The improved locking means comprises a wire loop 7 having offset portions 18—19, horizontal portions 20 and vertical legs 21. The legs 21 are adapted to seat in the openings 16 with the horizontal portions 20 resting in the recessed portion 15 formed in the bottom flange. It will be noted that the offset portions 18 of the loop extend

a short distance into the slotted portion of the upper flange and contact therewith in order to prevent tilting of the loop when it is in the operative position.

5 In assembling the device, wire loop 17 is placed in position on the block with legs 21 seated in the openings 16. This is accomplished by first inserting a leg in one of the openings and pushing the other end of the wire along the length of 10 the slot 14 until the other leg can be seated in its corresponding opening. When the loop is in this position the horizontal portions 20 are in the recesses 15, the upper surfaces of portions 20 being flush with the surface of flange 6. The flier wire 15 is then applied to the block by bending it in the form of a loop and slipping the looped portion down over the top flange 5. It will be understood that offset portions 18 formed in the loop 17 can be moved out of contact with the slot 14 to 20 give sufficient clearance for the flier wire to seat in the groove. After the central block engaging section of the flier wire is seated in the groove 7, the arms 9 of the wire are bent outwardly so that they are in line with the slotted portion of 25 the block.

With the above described arrangement, the flier wire is securely attached to the block during normal operation of the block, however, it can be readily detached for the purpose of replacing it 30 with another wire or for other reasons. Since the flier wire overlaps the horizontal portions 20 of the wire loop 17, it will be appreciated that any upward pull or thrust on the loop will tend to wedge the flier wire into tighter engagement with 35 the groove. By undercutting the upper flange 5, flier wires of various diameters can be accommodated and throughout the range of diameters for which the present block is designed, the wires will be tightly held in the groove and in contact with 40 the inner surfaces of the flanges.

It will be noted that the offset portions 13 of the flier wire are in mutual engagement with offset portions 19 of the loop 17, when the flier wire is seated in the wire receiving groove, thus preventing movement of the flier wire with respect 45 to the block.

Since offset portions 18 of the loop extend into the slot formed in flange 5, the loop cannot move laterally and the flier wire is retained in the 50 groove due to its mutual interlocking with portions of the loop.

Referring to Fig. 2, there is disclosed a bobbin 21 mounted upon a spindle 22 having an upper section 23 of uniform diameter, adapted to support a freely rotatable flier block 4'. The bobbin is also provided with a bushing 24 having an inwardly projecting flanged portion 25. The block 4' is similar in construction to the arrangement 55 shown in Fig. 1, however, differs from it in that it is provided with an additional peripheral groove 26 adapted to receive a removable foot member 27. This arrangement is intended for use with bobbins having end bushings and enables the block to be locked to the bobbin during normal 60 operation of the device. The foot 27, which may be formed of wire or other suitable material, is eccentric with respect to the body of the block and projects inwardly beyond the edge of the flanged portion 25 of the bushing. In this manner, the block is securely attached to the bobbin 65 and at the same time is free to rotate about the spindle.

It is sometimes desirable to provide thread guiding and tensioning means in addition to that 70 afforded by the flier wire. In the present ar-

rangement, I have incorporated a thread tensioning and guiding device with the flier wire locking means comprising a wire loop 28 formed with an eyelet 29 of suitable configuration. By means of this construction, additional tensioning is provided for the thread, which may be readily substituted for the flier wire fastening means used in connection with the block shown in Fig. 1.

It will now be appreciated that I have provided an improved flier block assembly, including flier 80 wire locking means, which is of general application with bobbins and spindles of various types. If the arrangement shown in Fig. 1 is used, the block is retained on the spindle by means of a mill nut 30. For bobbins having an end bushing, the 85 block shown in Fig. 2 is used.

While I have shown and described the preferred embodiment of my invention, I wish it to be understood that I do not confine myself to the precise details of construction herein set forth, by way of 90 illustrations, as it is apparent that many changes and variations may be made therein, by those skilled in the art, without departing from the spirit of the invention, or exceeding the scope of the appended claims.

What is claimed is:

1. A flier block comprising a centrally apertured body portion having flanges formed thereon, said flanges defining a peripheral flier wire receiving groove and a slot in the block extending across the top and along a diameter thereof adapted to receive flier wire retaining means.

2. A flier block comprising a centrally apertured body portion having flanges formed thereon, said flanges defining a peripheral flier wire receiving groove and a slot in the block along a diameter thereof adapted to receive flier wire retaining means, said slot extending across the top of the block and being of a depth greater than the width of the flier wire groove.

3. A flier block comprising a centrally apertured body portion having two flanges formed thereon, said flanges defining a peripheral flier wire receiving groove and a slot in the block along a diameter thereof adapted to receive flier wire retaining means, said slot being of a depth greater than the width of the flier wire groove and extending into the lower flange.

4. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in line with its slotted portion, and flier wire fastening means seated in the openings.

5. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in line with its slotted portion, and flier wire fastening means comprising a wire loop having straight leg portions seated in the openings formed in the bottom flange.

6. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in 145

- line with its slotted portion, and flier wire fastening means comprising a wire loop having each of its free ends formed with a horizontal portion and a vertical leg portion, said horizontal portion resting in the slot formed in the bottom flange, the leg portions being seated in the openings in said flange. 5
7. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in line with its slotted portion, and flier wire fastening means comprising a wire loop having each of its free ends formed with a vertical leg, a horizontal portion and an offset portion, said horizontal portion resting in the slotted part of the bottom flange, the vertical legs being seated in the openings in said flange, with the offset portion positioned in the opening formed by the slot at the top of the block. 10
8. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in line with its slotted portion, and flier wire fastening means comprising a wire loop provided with thread guiding means, each of the free ends of the loop being formed with vertical legs seated in the openings formed in the bottom flange. 15
9. A flier block assembly comprising a centrally apertured body portion having two flanges formed thereon, said flanges defining a peripheral flier wire receiving groove, a slot in the block extending across the top and along a diameter thereof terminating in the flange positioned below the groove, said flange having openings therein in line with its slotted portion, flier wire fastening means comprising a wire loop provided with thread guiding means, each of the free ends of the loop being formed with a vertical leg, a horizontal portion and an offset portion, said horizontal portion resting in the slotted part of the bottom flange, the vertical legs being seated in the openings in said flange and an offset portion, said horizontal portion resting in the slotted part of the bottom flange, the vertical legs being seated in the openings in said flange and a flier wire in the peripheral groove resting upon the horizontal portion of the wire loop and in contact with the offset portions thereof. 20
10. A flier block assembly comprising a centrally apertured body portion having flanges formed thereon, said flanges defining a peripheral flier wire receiving groove, a slot in the block extending across the top and along a diameter thereof adapted to receive flier wire retaining means, a second peripheral groove spaced from said wire receiving groove and a foot member seated in said peripheral groove. 25
11. A flier block comprising a centrally apertured body portion having flanges formed thereon, said flanges defining a peripheral flier wire receiving groove, a slot in the block along a diameter thereof adapted to receive flier wire retaining means, said slot being of a depth greater than the width of the flier wire groove, a second peripheral groove spaced from the wire receiving groove and a foot member formed of wire seated in said second groove. 30
12. A flier block comprising a centrally apertured body portion having two flanges formed thereon, the upper flange being under-cut to form an acute angle with the lower flange, said flanges defining a peripheral flier wire receiving groove and a slot in the block extending across the top and along a diameter thereof, adapted to receive flier wire retaining means. 35
13. A flier block comprising a centrally apertured body portion having two flanges formed thereon, the upper flange being under-cut to form an acute angle with the lower flange, said flanges defining a peripheral flier wire receiving groove and a slot in the block along a diameter thereof adapted to receive flier wire retaining means, said slot being of a depth greater than the width of the flier wire groove and extending into the lower flange. 40
